UNITED STATES PATENT OFFICE.

FERDINAND G. HENRY, OF NEW YORK, N. Y., ASSIGNOR TO BURKHART CORPORATION, OF BUFFALO, NEW YORK, A CORPORATION OF NEW YORK.

SHOE-POLISHING MECHANISM.

1,210,070.

Specification of Letters Patent. Patented Dec. 26, 1916.

Application filed May 19, 1914. Serial No. 839,587.

To all whom it may concern:

Be it known that I, FERDINAND G. HENRY, a citizen of the United States, residing at New York, in the county of New York and 5 State of New York, have invented certain new and useful Improvements in Shoe-Polishing Mechanisms; and I do hereby declare the following to be a full, clear, and exact description of the invention, such as 10 will enable others skilled in the art to which it appertains to make and use the same.

This invention relates to shoe polishing machines and has for an object to provide a mechanism of the same general type as that 15 disclosed in application 816,272, filed February 3rd, 1914, in the name of Charles F. Burkhardt with improved means for operation and improved means for carrying the polishing fabric.

20 A further object of the invention is to provide an improved means for converting a rotary motion into an oscillating motion transmitted to the polishing heads.

A further object of the invention is to 25 provide an improved polishing head.

With these and other objects in view the invention comprises certain novel constructions, combinations and arrangement of parts as will be hereinafter more fully described and claimed.

In the drawings: Figure 1 is a view of the device with parts of the housing broken away, the general structure being shown in perspective and the polishing heads in operative position. Fig. 2 is a view of the device with the polishing heads in inoperative position seen also in perspective. Fig. 3 is a perspective view of one of the polishing heads. Fig. 4 is a sectional detail view 35 of part of the polishing head. Fig. 5 is a detail view in side elevation of a fragment of the fabric holder. Fig. 6 is a detail sectional view through the fabric holder and adjusting means. Fig. 7 is a detail view of 40 the fabric holder in side elevation. Fig. 8 is a perspective view of the mechanical movement employed to impart an oscillating movement to the polishing heads.

Like characters of reference designate 50 corresponding parts throughout the several views.

The present invention comprises a pair of polishing heads indicated as organized structures at 10 which said polishing heads 55 are carried upon a yoke 11 adapted to raise

and lower between the positions shown at Figs. 1 and 2 from the operative position shown at Fig. 1 and the inoperative position shown at Fig. 2. To raise and lower such heads the trunnions 12 of the yoke 11 are provided with gears 13 which engage other gears 14 carried upon a shaft 15 which in turn carries a pinion 16 engaged by a rack 17, the latter being precipitated longitudinally by a cam 18 carried by a gear 19. The gear 19 receives rotary motion from a worm 20 carried by a shaft 21 which receives motion from a driving shaft 22 in any approved manner as by the pinion 23 and gear 24 and the beveled gears 25. It is obvious 70 that as the shaft 21 rotates the worm 20 will tend to rotate the cam 18 which will raise and lower the rack 17 thereby oscillating the gears 14 which being interengaged with the gears 13 also oscillate the trunnions 12 and the yoke 11 therewith to raise the yoke from the position shown at Fig. 1 to the position shown at Fig. 2 or reverse. The yoke 11 also carries a housing 26 mounted to oscillate upon a shaft 27 which is in alignment with the axis of the trunnions 12 and is provided with a beveled gear 28 taking motion from a gear 29 carried upon the shaft 21. It is obvious, therefore, that the yoke 11 may be raised and lowered without 85 affecting the engagement of the gears 28 and 29. The shaft 27 also carries a beveled gear 30 which engages a gear 31 upon a shaft 32 which extends into a housing 33 forming a part or an enlargement in the center of the 90 yoke 11.

The shaft 32 within the housing 33 is provided with a crank 34 carrying a pin 35 disposed at an angle to the axis of the shaft 32 and transecting the axis of shafts 36 95 which are also journaled in the yoke 11. These shafts 36 carry a ring 37 rigidly connecting such shafts with the pin 35 extending through such ring and embraced by a bearing block 38 which is also pivoted at 100 37 to such ring. It is obvious, especially from an examination of Fig. 8 that the rotation of the shaft 32 will cause the pin 35 to describe two cones with their apices meeting at the axis of the shafts 36 and that as 105 said pin 35 rotates it will cause the said ring 37 and shafts 36 to oscillate. The shafts 36 are provided with gears 40 engaging other gears 41 carried upon shafts 42 which carry the polishing heads 10. It 110

will be apparent, therefore, that as the shaft 21 rotates it not only serves to raise and lower the polishing heads at intervals determined by the cam 18 but also serves to oscillate the polishing heads upon their journals 42. It is intended to drive the polishing heads only a certain period of time during the operation of the entire mechanism but the matter of intermittent drive forms 10 no part of the present invention and so far as the present invention is concerned the polishing heads will be lowered to operative position and oscillated during the greater portion of the revolution of the gear 19 and 15 will be quickly raised from such operative position as shown in Fig. 1 to inoperative position as shown at Fig. 2, such raising and lowering, however, not interfering in any way with the oscillation of such polishing heads.

The polishing heads themselves comprise a frame consisting of a cross-bar 43 and pins 44 rigid with the bar 43 and arranged in parallelism. Mounted upon such pins 25 44 are sleeves 45 rigidly and preferably integrally connected by a rib 46 and rotatable upon such pins 44. The sleeves 45 carry pins 47 rigidly secured thereto and extending from each of such pins 44 toward 30 the other. Upon the pins 47 sleeves 48 are slidably mounted with springs 49 controlled by tension nuts 50 for exerting tension upon such sleeves 48.

Hinged to the sleeves 48 are fabric carriers 51 which are similar to the fabric carriers disclosed in Patent 1,051,387, issued January 28, 1918, upon the application of Charles F. Burkhardt and comprise tubes slotted along their under sides as indicated 40 at 52, curved downwardly as indicated at 53 and carrying the fabric 54 by means of a roll or other enlargement 55 formed integral with or separate from such fabric 54, as best shown at Figs. 3, 4 and 6. The 45 relation of the fabric 54 to the sleeves 48 is such that the tension of the springs 49 serves to hold such fabric taut but to permit the sleeves 48 to slide on the pins 47 against the tension of such springs 49 to assume a 50 curved position. Such curvature is permitted by the sleeves 45 moving rotatably upon the pins 44 as the fabric 54 is bulged to produce such curvature. The fabric carriers 51 are pivoted to the sleeves 48 by means of 55 ears 56 which also carry adjusting screws 57, by the adjustment of which the sleeves 48 may be held at such distance from the sleeves 45 that the fabric 54 need not in inoperative position be taut but may assume 60 any degree of looseness which is found desirable.

In operation the shoe to be operated upon will be placed in such position that when the polishing heads are in the position 65 shown at Fig. 1 the fabric 54 will bear with

considerable tension upon the shoe and cause such fabric to assume an arcuate or bulged condition with the shoe within such arc and when such polishing head oscillates upon its shaft 42 will draw the fabric alternately in 70 opposite directions over the shoe and at the same time tilt the head to polish not only the top of the shoe but the sides as well. It is obvious also that to polish over the curvature of the toe of the shoe it is necessary that the fabric be curved at that side for which purpose the fabric holder 51 is curved as at 53. It is also obvious that when the fabric holders 51 are tilted to provide a bulge in the fabric the position and 75 relation of the extremities 53 will be such as to produce a greater degree of looseness in the fabric at that edge than at any other point. It is also obvious that the springs 49 may be adjusted by the use of the nuts 50 to apply different degrees of tension to the opposite sides of the fabric as it is found necessary to apply greater frictional stress upon some parts than other parts of the shoe. It will thus be apparent that with the shoe in 80 position to be engaged by the polishing heads in the position shown at Fig. 1 and with the heads themselves in inoperative position as shown at Fig. 2 when the device starts to operate it starts at once to descend 85 to operative position and also the polishing heads start to oscillate. The result is that when the polishing head touches the shoe it is already in oscillating condition and does not bind upon the shoe as would be the case 90 if it engaged the shoe at rest and began its oscillation after such engagement. It is also obvious that by engaging the shoe when in oscillation it engages first at slight tension and the tension increases to complete 95 operative tension and that the reverse is true when the polishing head leaves the shoe, that is that it leaves the shoe while oscillating and reduces the frictional engagement so as not to leave the imprint of the fabric upon 100 the polished surface of the shoe.

I claim:

1. In a shoe polishing mechanism, a yoke mounted to oscillate upon alined trunnions; a shaft in alinement with the axis of the trunnions; polishing heads carried upon shafts journaled in the yoke at right angles to the first mentioned shaft; means to rotate the first mentioned shaft; and means to convert the rotary motion of such shaft to oscillating motion and transmit it to the said polishing heads.

2. In a shoe polishing mechanism, a frame adapted to be raised and lowered; polishing heads carried by the frame and adapted to oscillate; a shaft extending between the polishing heads; means connecting the shaft with the polishing heads to transmit motion to such heads; a second shaft journaled at right angles to the first mentioned shaft; 125

and means carried by the shafts to convert rotary motion from such second shaft into oscillating motion transmitted to the first mentioned shaft.

5 3. In a shoe polishing mechanism, a frame adapted to be raised and lowered; spaced polishing heads carried by the frame and journaled to oscillate; a shaft carried by the frame and intergeared with the polishing heads; a second shaft journaled in the frame; means to apply rotary motion to the second mentioned shaft; and means connecting the second mentioned shaft with the first mentioned shaft for converting such rotary motion into oscillating motion upon the first mentioned shaft.

10 4. In a shoe polishing mechanism; a frame adapted to be raised and lowered; a shaft journaled in the frame and adapted to oscillate; a cross-bar carried by the shaft; pins carried by and extending from the cross-bar; fabric carriers hinged upon the pins; and a fabric secured to and extending between the fabric carriers.

15 5. In a shoe polishing mechanism, a frame adapted to be raised and lowered; a shaft journaled to oscillate in the frame; a cross-bar carried by the shaft; pins carried by the cross-bar in parallelism; sleeves mounted to rotate upon the pins; fabric carriers yieldingly connected with the sleeves; and a fabric secured to and extending between the fabric carriers.

20 6. In a shoe polishing mechanism, a frame adapted to be raised and lowered; a shaft journaled to oscillate in the frame; a cross-bar carried by the shaft; pins carried by the

cross-bar in parallelism; sleeves mounted to rotate upon the pins; blocks carried by the sleeves and movable slidably and yieldably 40 toward each other; fabric carriers carried by the blocks; and a fabric secured to and extending between the fabric carriers.

7. In a shoe polishing mechanism, a frame adapted to be raised and lowered; a shaft journaled in the frame and adapted to oscillate; a cross-bar carried by the shaft; pins carried by the cross-bar in parallelism; sleeves mounted to rotate upon the pins; other pins extending from the sleeves toward each other; other sleeves mounted slidably upon the second mentioned pins; means to hold such second mentioned sleeves yieldingly away from each other; fabric carriers carried by the second mentioned sleeves and a fabric secured to and extending between the fabric carriers.

25 8. In a shoe polishing mechanism, a frame mounted to oscillate upon alined trunnions; polishing heads carried by the frame; a shaft mounted in parallelism with the trunnions; a second shaft; transmission mechanisms between the second mentioned shaft and the first mentioned shaft whereby the first mentioned shaft is oscillated; and transmission mechanism between the first mentioned shaft and the polishing heads whereby the polishing heads are oscillated.

In testimony whereof I affix my signature in presence of two witnesses.
